(57) **CLAIM**

The ornamental design for an earthquake alarm lamp, as shown and described.

DESCRIPTION

FIG. 1 is a front perspective view of an earthquake alarm lamp showing our new design;

FIG. 2 is a front plan view thereof;

FIG. 3 is a back plan view thereof;

FIG. 4 is a right-side elevational view thereof;

FIG. 5 is a left-side elevational view thereof;

FIG. 6 is a bottom plan view thereof; and,

FIG. 7 is a top plan view thereof.
